H. A. LUPLOW.
POOL BALL RACK.
FILED MAR. 23, 1922.

Fig. 2

Inventor,

Henry A. Luplow,
By his wife, *Frances S. Luplow*

UNITED STATES PATENT OFFICE.

HENRY A. LUPLAW, OF LAPORTE, INDIANA.

POOL-BALL RACK.

Application filed March 23, 1922. Serial No. 545,943.

To all whom it may concern:

Be it known that I, HENRY A. LUPLAW, a citizen of the United States, and a resident of Laporte, in the county of Laporte and State of Indiana, have invented certain new and useful Improvements in Pool-Ball Racks, of which the following is a specification.

This invention relates to improvements in racks for pool balls, and has for its principal object to produce a simple and durable device of the character described, capable of being easily manipulated to form the pool balls in their initial position at the beginning of the game.

The invention may best be understood by reference to the accompanying drawing, in which:

Fig. 1 is a plan view of a rack constructed in accordance with my invention, with a portion of the rim broken away, and

Fig. 2 is a side view of the device, with a portion broken away to show one side in cross section.

Racks for pool balls are usually triangular in general shape, and of proper size as to contain fifteen pool balls in close confinement in the usual triangular conformation. Such racks are usually made of wood, plastic composition, or a similar semi-resilient material, having plane vertical inner surfaces for engagement with the balls. In practice, the racks are preferably made somewhat larger than the exact boundary line of the balls owing to the difficulty of removing a close-fitting rack without disturbing the position of the balls. Furthermore, such racks, being relatively light in construction are often subject to breaking and warping.

In order to overcome these and other disadvantages inherent in the ordinary type of rack, I have provided improved features embodied in the rack illustrated which comprises a frame portion 10, preferably of a light strong metal such as aluminum, and a confining strip or rim 11, of a semi-resilient composition, such as a fiber or plastic compound. The frame portion 10 is provided with a flange 12 extending inwardly around its upper edge 13. The confining strip 11 covers the upper surface of the body portion 10, and has an inner margin 14 extending beyond the flange 12. Said strip is detachably connected to said

flange by a plurality of small bolts 15, 15, or their equivalents, extending into or through suitable bosses 16, 16 on the flange 12.

The confining strip 11 is of such height 60 in proportion to the size of the rack so that the margin 14 of the rim 11 engages the balls 17, 17 tangentially at the point of their maximum diameter. Therefore, when the rack is lifted from the balls, the engaging portion of the rim is immediately released from engagement with the balls, and considerable clearance is afforded between the frame portion 10 and the balls, thereby minimizing the danger of accidental contact or displacement of the latter. The rim 11 of my improved form of rack may therefore be made to fit the balls quite closely, and may be quickly manipulated to form the balls in their proper conformation, and 70 readily removed therefrom.

The metallic frame portion 10 may be relatively light in construction, being in proportion approximately half the height of the balls, which is less than the height of racks of 80 the usual type. The flange 12 affords a strengthening means to resist breakage and minimize warping of the device. The rim 11 covering the top of the frame 10, protects the balls from injury when they are 85 dropped into the rack in the usual manner. When the rim becomes worn or damaged, it may readily be replaced as desired.

I claim:

1. A rack for pool balls comprising a 90 metal frame provided with an inwardly extending bearing strip of semi-resilient material extending around the frame and adapted to engage the balls approximately at the point of maximum diameter. 95

2. A rack for pool balls comprising a metal frame and a strip of semi-resilient material extending around the upper edge of said frame and projecting inwardly therefrom to engage the balls approximately at 100 the point of maximum diameter.

3. A rack for pool balls comprising a metal frame having a flange along its upper edge, and a strip of semi-resilient material secured to said flange and extending inwardly to engage the balls approximately at 105 the point of maximum diameter.

4. A rack for pool balls comprising a metal frame, and a strip of semi-resilient material detachably secured to and surrounding the 110

upper edge of said frame and extending inwardly therefrom to engage the balls approximately at the point of maximum diameter.

5. A rack for pool balls comprising a metal frame, having a flange around its upper edge, and a strip of semi-resilient material

detachably mounted to said flange and projecting inwardly beyond the edge of said flange to engage said balls approximately at the point of maximum diameter.

In witness whereof, I hereunto subscribe my name this 21st day of March, A. D. 1922.

HENRY A. LUPLOW.
